UNITED STATES PATENT OFFICE

CHESTER L. DAVIS, OF KEOKUK, IOWA, ASSIGNOR TO WIRED RADIO, INC., OF NEW YORK,
N. Y., A CORPORATION OF DELAWARE

TELEVISION SYSTEM

Application filed December 18, 1929. Serial No. 414,957.

My invention relates broadly to television systems and more particularly to a television system employing electrical energy of variable frequency for the transmission and reception of pictures.

One of the objects of my invention is to provide a system of television wherein the customary apertured scanning disk at the television receiver is eliminated.

10 Another object of my invention is to provide a system for the transmission and reception of pictures or images by employing variable frequency electrical energy to effect the scanning.

15 Still another object of my invention is to provide a television system where the receiving screen is rendered variably luminous in accordance with the transmitted picture or image by virtue of potential nodes and anti-
20 nodes of electrical energy which are caused to move in predetermined manner over portions of the screen.

A further object of my invention is to provide a method for transmitting variable frequency energy according to the different areas of a transmitted picture and causing electrical nodes and antinodes at the receiver to directly and variously illuminate a receiving screen in accordance with the transmitted picture.

25 A still further object of my invention is to provide a television receiving system wherein the longitudinal and lateral displacement of potential nodes and antinodes of electrical energy are directly reproduced on the receiving screen proper.

30 Other and further objects of my invention reside in certain structure and arrangement of apparatus employed to carry out the operation of the system of television of my invention.

35 A better understanding of my invention can be had from the specification following and from the accompanying drawings
40 wherein:

45 Figure 1 illustrates diagrammatically the electrical relation of the apparatus employed; Fig. 2 shows a modified arrangement of the apparatus employed in my invention; Figs.
50 3, 4, 5, 6 and 7 illustrate schematically the

operation of the television system of my invention; Fig. 8 illustrates the arrangement for scanning employed at the transmitter; and Figs. 9 and 10 illustrate schematically the method of reproducing the transmitted 55 picture and image.

My copending applications Serial No. 299,501, filed August 14, 1928, and Serial No. 300,979 filed August 21, 1928, describe a system of television and apparatus therefor to 60 which the present embodiment is similar in many respects. The former relates particularly to the receiving screen, the latter to the system in general and the present relates to certain improvements of both the above applications. The principal feature of operation of the system of television of my invention resides in the use of a directly responsive receiving screen, caused to luminously respond by virtue of potential nodes and antinodes 65 of electrical energy in accordance with the variable frequency energy which in turn corresponds to the respective areas of the transmitted picture or image. 70

Figure 1 of the accompanying drawings 75 illustrates in general the arrangement of apparatus employed in the television system of my invention. The receiving screen comprises a plurality of luminously responsive inductance sections 1, 2, 3, 4, 5, 6, 7, 8, 9, 10, 80 11 and 12, arranged in the same plane and retained in position by means of a suitable framework 13. Each section of the inductance comprises an elongated glass or quartz tube having a wire or coiled wire extending 85 the length thereof. It is not essential that this wire or coil of wire be placed within the elongated tube as will appear in the description following. The several inductance sections are connected in series electrically 90 whereby the total inductance of the receiving screen is the sum of the inductance of the several sections. The receiving screen is caused to be luminous by means of high frequency energy generated by oscillator 14. 95 This will be described in detail later. Oscillator 14 is caused to develop modulated high frequency energy by virtue of modulator 15. The modulation system shown is that of the constant current type where the sum of the 100

oscillator and modulator plate current remains constant, however it is obvious that other systems of modulation may be employed. A source of modulated energy is coupled to modulator 15 through transformer 16, the primary being associated with the low frequency line or with the output of an amplifier. The amplifier may be associated with a radio receiving set or a line wire system as shown at 17. The line wire system is shown for purposes of illustration. The line wire system is connected to the amplifier 18 which is designed to amplify variations of current caused by photoelectric cell 19. Photoelectric cell 19 is designed to be actuated by variations of luminous energy directed thereto by scanning disk 20. Disk 20 may be driven by a suitable motor 21.

The operation of the system may be learned from Fig. 1 of the drawings. Oscillator 14 is caused to generate high frequency oscillations in the associated tank circuit 22. Load circuit 23 is coupled to circuit 22 in such manner as to effect a transfer of energy. Tank circuit 22 and load circuit 23 are preferably adjusted to near resonance and maintained in such adjustment. The load circuit 23 also includes variable condensers 24 and 25 and the luminously responsive inductance screen connected as shown. The capacity of condensers 24 and 25 is continuously changed by any suitable rotating motor 26. These condensers 24 and 25 are so connected to motor 26 that the capacity is varied in opposite order. Thus while condenser 24 is increasing in capacity condenser 25 is decreasing in capacity, and vice versa. It is obvious therefore that the frequency characteristics of the load circuit do not change. Assuming that the load circuit is adjusted to resonance with the tank circuit, standing or stationary waves will be set up in the load circuit. Since the luminously responsive inductance screen is a part of this load circuit, the standing waves will be luminously visible by virtue of the gaseous content in the tubular sections 1, 2 to 12. A potential node thus established along some section of the screen is indicated by the relative intensity of the sections and the different parts of each section. Thus where the crest of the potential is located, there will be a luminous spot. As the capacity of condensers 24 and 25 is varied it follows that the position of such luminous spot will be likewise varied. Providing this spot is moved along the different sections in progressive order similar to the movement of the scanning member 20 at the transmitter, the screen will reproduce the picture transmitted. The intensity of the luminous spot above referred to will be proportional to the modulation of the high frequency energy from oscillator 14 and this in turn is proportional to the resistance of the photoelectric cell 19 or the respective light and dark areas of the transmitted picture.

It will be noted that the adjustment of condensers 24 and 25 must be accomplished in synchronism with the movement of the scanning member 19 at the transmitter.

Fig. 2 shows an alternative arrangement at the receiver. In this arrangement variable inductance members such as variometers 24a and 25a are substituted for variable condensers 24 and 25 shown in Fig. 1. The principle of operation is the same as above described, the variometers being continuously adjusted in opposite order which is effective in shifting the potential node and antinode established in the luminously responsive inductance screen.

A better understanding of the system and method of operation can be had from Figs. 3, 4, 5, 6 and 7 which show five successive steps in the operations of scanning and reproducing. In Fig. 3 the potential crest is established near the top of the screen as indicated at X which is manifested as a luminous spot. The scanning disk 20 employed at the transmitter is shown as of the double spiral type, the two spirals being indicated by the reference characters *a* and *b*. Spirals *a* and *b* are adapted to scan alternate parallel lines across the picture to be transmitted, such as the first aperture in spiral *b* scanning the line intermediate the lines scanned by the first and second apertures of spiral *a*. As shown, these alternate lines are scanned or filled in only after the lines scanned by spiral *a* are completed. As the first aperture in spiral *a* moves across the image or picture H, luminous spot X is shifted in a line to the right of the point of origin. As shown by the dotted arrows on the inductances 30 and 31, inductance 30 is set to a minimum value while inductance 31 is set to a maximum value. For purpose of illustration, the decrease of inductance is effected by progressively increasing the portion of the respective inductances short-circuited by the movable arms.

Fig. 4 shows another step in the operation wherein the luminous spot X has moved from line 1 near the top of the screen to line 5 progressively along lines 2, 3 and 4 although on lines 2 and 4 there is no luminosity. The dotted lines 2, 4, 6, 8, 10 and 12 indicate the inactive inductance sections, the solid lines 1, 3, 5, 7, 9 and 11 indicating the active inductance sections cooperating with the movement of spiral *a* on the transmitting disk. The inactive lines are rendered thus by providing the spacing of the apertures in the scanning disk equal to two times the width of the image H plus a small length allowing for the small inductance of the connectors between the consecutive sections of the luminous inductance. As shown in Fig. 4 the luminous spot X is on line 5 at the left thereof and the third aperture in spiral *a* of the transmitter scanning disk is at the left of the transmitted image H.

Fig. 5 shows another progressive step in the operation, where spot X on the receiving screen has advanced one line, where the fourth aperture in spiral a has reached the left side of image H and where inductance 30 and inductance 31 are of substantially equal inductance value. Fig. 6 shows another step where spot X has advanced one line, the fifth aperture in spiral a is at the left of image H, inductance 30 has increased in value and inductance 31 has decreased in value. Fig. 7 shows still another step where spot X has started across line 2, which line was heretofore inactive, the first aperture of spiral b has already advanced part way across image H and inductances 30 and 31 have again changed in values. The active lines with spiral b are here shown as heavy lines the inactive being dotted as before. The only reason that alternate lines are inactive is that there is no modulation at those particular times. The potential antinode is, theoretically at least, present along the inactive lines but since there is no modulation of the energy, due to the spacing of the apertures in the transmitter scanning disk, no luminous response is indicated along these lines. Due to the connection of the inductance sections it is obvious that without such a provision, luminous spot X would first move from left to right and then from right to left. The effect of causing always the movement in the same direction may be produced by employing relatively large values of inductance in each section proper of the screen and employing connectors between the sections where the connectors have a negligible inductance value. The slight inductance values of the connectors may therefore be offset in effect by spacing the apertures in the transmitter scanning disk accordingly, employing if desired a single spiral disk.

Fig. 8 shows in detail the arrangement of the apertures in the scanning disk to effect scanning of alternate lines by the use of two spirals. Fig. 9 shows the scanning of the lines a, e, e, g, i and k effected by one spiral. Fig. 10 shows lines b, d, f, h, j and l by the other spiral. Figs. 8, 9, and 10, taken together show the respective lines drawn across the image H corresponding to the different radii of the apertures in the two spirals of the scanning disk employed at the transmitter. The manner in which the interleaving of the lines scanned is clearly shown.

Electric motors 21 and 26 are illustrated as being energized from a like source of current to insure synchronous operation of both the transmitter and receiving mechanism. The variable frequency adjustment at the receiver is accomplished in timed relation with respect to the movement of the scanning disk at the transmitter. The television system of my invention is adapted to use with wired

radio, space radio or low frequency telephone or telegraph transmission lines.

Among the advantages of the television system of my invention over systems heretofore proposed is the advantage of dispensing with the usual scanning disk at the receiver. In the system of my invention, the receiving screen may be constructed of any suitable size, such as is suitable for home entertainment or for theatre use. A system of "chain theatres" supplied with pictures from a central studio, may be easily established in a manner much similar to the "chain" broadcasting stations now in operation.

I realize that there are many possible modifications of my invention, departing from the accompanying drawings and foregoing specification only in details and it is to be understood that the embodiments of my invention are in no way to be restricted by the foregoing specification or by the accompanying drawings but only by the scope of the appended claims.

What I claim as new and desire to secure by Letters Patent of the United States is as follows:

1. In the art of transmitting vision, the combination of a luminously responsive inductance screen, a series circuit connected with said inductance and resonantly responsive to signaling energy for establishing nodes and antinodes of potential along said inductance screen, variable impedance elements disposed in said series circuit for varying the position of said nodes and antinodes by varying the electrical relation of said inductance screen with respect to said series circuit while maintaining the frequency characteristics of said series circuit and said inductance screen constant.

2. In a television system, the combination of a luminously responsive inductance screen comprising a plurality of parallel sections connected in series, an associated energy supply circuit and means for continuously and progressively changing the electrical relation of said inductance screen with respect to said supply circuit while maintaining the frequency characteristics of said inductance screen and energy supply circuit constant.

3. In the art of transmitting vision, means for transmitting television signaling energy over a variable frequency range, a luminously responsive inductance screen, an energy supply circuit for impressing the variable frequency signaling energy on said screen and means for continuously changing the electrical relation of said inductance with respect to said energy supply circuit at a rate determined by the rate of transmission of the television signalling energy.

4. In the art of transmitting vision, means for scanning an object and transmitting signaling energy over a variable frequency

range, a luminously responsive inductance screen, an energy supply circuit for impressing the variable frequency signaling energy on said screen and means for changing the electrical relation of said inductance screen with respect to the energy supply circuit at a rate determined by the rate of scanning the object at the transmitter.

5. In the art of transmitting vision, means for transmitting television signaling energy, a luminously responsive inductance screen, a signal receiving circuit connected in series with said screen, a continuously variable impedance disposed in said signal receiving circuit, said screen comprising a plurality of parallel sections disposed in the same plane and connected in series at the ends thereof, means for establishing potential antinodes along different parallel sections of said luminously responsive inductance screen and means operating said continuously variable impedance at a rate determined by the rate of transmission of the television signaling energy.

25. 6. In the art of transmitting vision, means for transmitting television signaling energy, a luminously responsive inductance screen, a signal receiving circuit connected in series with said screen, a continuously variable impedance disposed in said signal receiving circuit, said screen comprising a plurality of parallel sections disposed in the same plane and connected in series at the ends thereof, scanning means whereby antinodes of potential are caused to traverse parallel sections of a luminously responsive inductance screen.

7. A television system comprising means for transmitting television signaling energy over a variable frequency range, an inductance screen at a receiver, an oscillator for continuously exciting said inductance screen, a modulator for controlling the effect of said oscillator upon said inductance screen in accordance with the operation of said transmitting means, and a circuit coupling said oscillator with said inductance screen including an impedance element and means for varying the effective value of said impedance at a rate determined by the rate of operation of said transmitting means.

8. A television system comprising means for transmitting television signaling energy over a variable frequency range, an inductance screen at a receiver, an oscillator, a circuit interconnecting said oscillator with said inductance screen whereby said oscillator operates to continuously energize said inductance screen, said circuit including a pair of variable impedance elements connected in series with said inductance screen, and means for periodically changing the effective values of said variable impedance elements at a rate dependent upon the rate of operation of said transmitting means.

65. 9. A television system comprising means

for transmitting television signaling energy over a variable frequency range, an inductance screen at a receiver, an oscillator, a transformer system connected with the output of said oscillator, said transformer system including primary and secondary windings, a series circuit including said secondary winding and said inductance screen, independent variable condenser elements connected in series with said inductance screen and disposed in circuit adjacent opposite ends of said secondary winding, and means for periodically varying the effective values of said condensers at a rate determined by the rate of operation of said transmitting means.

10. A television system comprising means for transmitting television signaling energy over a variable frequency range, an inductance screen at a receiver, an oscillator, a transformer having primary and secondary windings with the primary winding thereof connected with the output of said oscillator, a connection between said secondary winding and said inductance screen and separate condenser elements connected in series with said inductance screen adjacent opposite ends of said secondary winding, one of said condensers being variable for increasing the effective capacity thereof while the other of said condenser elements is variable in an opposite sense for decreasing the capacity thereof, and means for operating said condensers at a rate determined by the rate of operation of said transmitting means.

11. A television system comprising means for transmitting television signaling energy over a variable frequency range, an inductance screen at a receiver, an oscillator, a coupling transformer including primary and secondary windings, a connection between said primary winding and the output of said oscillator, and a circuit extending between said inductance screen and said secondary winding, said circuit including a pair of impedance elements, one of said impedance elements being connected in circuit with said inductance screen adjacent one end of said secondary windings and the other of said impedance elements being connected in said series circuit adjacent the opposite end of said secondary winding, and means for periodically varying the effective values of said impedance elements at a rate determined by the rate of operation of said transmitting means, one of said impedance elements being effectively variable in a sense opposite to the variation of the other of said variable impedance elements.

In testimony whereof I affix my signature.
CHESTER L. DAVIS.
